US00D670280S

(12) **United States Design Patent**
Rayner

(10) **Patent No.:** **US D670,280 S**
(45) **Date of Patent:** **** Nov. 6, 2012**

(54) **CASE FOR AN ELECTRONIC DEVICE**

(75) Inventor: **Gary Rayner**, Lemon Grove, CA (US)

(73) Assignee: **Treefrog Developments, Inc.**, San Diego, CA (US)

(**) Term: **14 Years**

(21) Appl. No.: **29/399,118**

(22) Filed: **Aug. 9, 2011**

(51) **LOC (9) Cl.** **14-03**

(52) **U.S. Cl.** **D14/250**

(74) *Attorney, Agent, or Firm* — Lathrop & Gage LLP; Sean M. Coughlin, Esq.

CLAIM

The ornamental design for a case for an electronic device, as shown and described.

DESCRIPTION

FIG. 1 is a drawing of a front exterior view of a case for an electronic device.

FIG. 2 is a drawing of a view of the exterior left side of a case for an electronic device.

FIG. 3 is a drawing of a view of the exterior right side of a case for an electronic device.

FIG. 4 is a drawing of a top exterior view of a case for an electronic device.

FIG. 5 is a drawing of a bottom exterior view of the design for a case for an electronic device; and,

FIG. 6 is a drawing of a first embodiment of an exterior back view of the design for a case for an electronic device.

The broken lines represent boundaries of the claim and form no part thereof.
